UNITED STATES PATENT OFFICE.

JOHN FIELDING, OF PROVIDENCE, RHODE ISLAND, ASSIGNOR OF ONE-HALF TO
JOSEPH P. WHITAKER, OF APPONAUG, RHODE ISLAND.

SAFETY-CATCH.

1,382,635.

Specification of Letters Patent. Patented June 28, 1921.

Application filed November 24, 1920. Serial No. 426,887.

To all whom it may concern:

Be it known that I, JOHN FIELDING, a citizen of the United States, residing at Providence, in the county of Providence and 5 State of Rhode Island, have invented certain new and useful Improvements in Safety-Catches, of which the following is a specification.

This invention relates to improvements in 10 catch members for pin tongues, used more particularly on cuff pins, brooches and the like; and the object of this invention is to provide an improvement in so-called safety catches without employing moving parts, 15 whereby the pin tongue, by proper manipulation, may be caused to readily enter or leave the catch, but which cannot inadvertently become disengaged therefrom.

The nature and advantages of the invention 20 will be better understood when the following detail description is taken in connection with the accompanying drawings, the invention residing in the combination and arrangement of parts as claimed.

25 In the drawings forming part of this specification, like numerals of reference indicate similar parts in the several views and wherein:—

Figure 1 is a side elevation showing my 30 improved catch as mounted on a base with the pin stem in engagement therewith.

Fig. 2 is an end view of my improved catch member.

Fig. 3 is a view illustrating the catch 35 member as cut from sheet stock before being folded into finished shape.

Fig. 4 is a modified form of my improved catch.

With reference to the drawings, 10 designates a base plate which may be considered as representing a brooch, cuff pin, or the like, to which the base portion 11 of my improved catch member may be attached or connected in any suitable way. This catch 45 member is preferably formed of sheet stock having a body portion 12 with two laterally, oppositely-extending wings 13^a and 13. The upper end of this body portion is then bent over into hook form as at 14 providing 50 a broad-faced, hook-shaped hood with its upper lip or engaging edge 15 formed on an angle relative to the base of the brooch, the edge 16 of the lip nearest the joint end 17 of the brooch being longer or extending

nearer to the base than the opposite edge 55 18 thereof.

The side wings 13 and 13^a are bent forward providing spaced apart, lower guard and guide lips which are of sufficient length to extend forwardly and project beyond the 60 front of the upper lip 15 of the hood thereby providing a rest and a guide against which the end of the pin stem 20 may seat to be guided laterally into and out of the catch after its body portion has been sprung down 65 to proper alinement to pass said opposite lips as presently described.

It will be noted that the lower guide lip 13 on the edge of the catch opposite to that of the downwardly-extending portion 16 on 70 the hood, is somewhat longer than the lip 13^a opposite this downwardly extending portion 16, whereby an angular space 21 is formed between the upper and lower edges or lips of the mouth or opening into the 75 hook, necessitating the bending or springing downward the body portion of the pin stem, or that portion of the pin stem intermediate the catch and joint, out of its normal alinement or toward the base, to permit its end 80 portion to pass said opposite extensions 13 and 16 in either entering or leaving the catch.

I do not wish to be restricted to the angular shaping of the lips at the mouth, as any 85 oppositely-projecting extending portions on the opposite lips such for instance as that illustrated in Fig. 4, which are out of vertical alinement with each other and are so arranged that the body of the pin stem must 90 be sprung inwardly out of its normal alinement toward its base, to permit its end portion to pass these said extensions in either entering or leaving the catch, will fall within the spirit and scope of this invention. 95

It is found in practice that normally when the brooch or pin which is in operative position and the pin stem 10 has been passed through the fabric to which the brooch is attached a bunch of the fabric between the 100 base 10 and pin stem 20 normally crowds or forces the pin stem up into the hood portion of the catch member and the natural pressure of this fabric against the pin stem 105 is to bow or bend it outwardly or away from the base, or in the direction opposite to that necessary to cause it to be released by the catch.

Therefore in order to release the pin stem it is necessary to be pressed and sprung inwardly by the hand of the user in order to place it in the necessary alinement to be released from the catch.

5 The device is extremely simple and practical in construction and effective in its operation and by its use a safety catch device is provided without the use of moving parts, 10 which effectually prevents the inadvertent release of the pin stem from its catch.

15 The foregoing description is directed solely toward the construction illustrated, but I desire it to be understood that I reserve the privilege of resorting to all the mechanical changes to which the device is susceptible, 20 the invention being defined and limited only by the terms of the appended claims.

I claim:

20 1. A catch member for pin tongues comprising a broad-faced hook-shaped hood, a lower guard and guide lip extending forwardly beyond the front edge of said hood, and oppositely projecting extending portions 25 on said hook and lower lip out of vertical alinement with each other guarding the mouth of the catch and so arranged that the body portion of the pin tongue must be sprung inwardly out of its normal alinement to permit its end portion to pass said

extensions in either entering or leaving said catch.

2. A catch member for pin tongues having a base, a hook-shaped hood portion open at its side to receive the pointed end of the pin tongue, said catch being provided with a lower guard and guide lip extending laterally beyond the forward edge of said hood to serve as a rest for and to guide the pin tongue laterally into and out of the hood, the 40 entering edges of said hood and said guide being both set at an angle to the plane of the base, whereby the body of the pin tongue must be sprung inwardly out of its normal alinement to either enter or leave said catch. 45

3. A catch member for pin tongues having a base, a hook-shaped hood portion open on its side to receive the pointed end of the pin tongue, said catch being provided with a pair of spaced apart lower guard and 50 guide lips extending forwardly beyond the front edge of the hood to engage and guide the pin tongue laterally into the hood, the entering edge of said hood and said lips being set to form a laterally-inclined mouth 55 whereby the body of the pin tongue must be sprung inwardly out of its normal alinement to either enter or leave said catch.

In testimony whereof I affix my signature.
JOHN FIELDING.
